CONTROLLING ARRANGEMENT FOR
SETTING ORGANS

Ferdinand Eduard Lutz, Berlin, Germany, assignor to Telefunken Gesellschaft für Drahtlose Telegraphie m. b. H., Berlin, Germany, a corporation of Germany

Application June 30, 1938, Serial No. 216,775
In Germany July 1, 1937

4 Claims. (Cl. 172—239)

The present invention relates generally to remote control devices and more particularly to an arrangement for controlling the operation of a motor from a remote point. A particular application of the present invention is in connection with signalling apparatus where it is desired to tune a radio receiver from a remote point.

In ordinary remote control devices there is no provision for making compensating or fine adjustments from the remote point so that once the various station setting devices are fixed at the receiver it is not possible from the remote point to compensate for slight detuning such as is caused, for instance, by temperature fluctuations. In certain types of work as, for instance, in airplane direction finding installation it is inconvenient to make adjustments at the receiver since the receiver is usually mounted at a distance from the pilot's position.

It is an object of the present invention to devise a remote control arrangement which includes means for making compensating or fine adjustments from the remote point thus permitting exact tuning under all conditions.

A preferred embodiment of the invention is illustrated in the drawings wherein:

Fig. 1 is a circuit diagram illustrating an arrangement constructed in accordance with the present invention for controlling a motor from a remote point;

Fig. 2 is a diagrammatic representation of the layout of the switches;

Figs. 3, 4 and 5 illustrate the operating contacts and one set of levers in various positions; and,

Fig. 6 is a side view of a section of the lever assembly.

From a consideration of Fig. 1 it will be seen that the invention provides a motor drive device M which is connected to any instrumentality to be driven such as the tuning means of radio receiving apparatus. The motor is energized by current derived from a battery B which may be any suitable source of current. Several circuits are provided for connecting the motor M to the battery B. One of these connects the motor M to the battery B through section b₁ of switch assembly b, coarse adjustment switch a and switches 1 and 2. It will be noted that switch a is a polarity reversing switch and that when switch b₁ is closed and switches 1 and 2 are closed the motor M may be operated in reverse or forward as desired by simply throwing the switch a to its extreme upper position for rotation of the motor M in one direction, and to its

extreme lower position for rotation of motor M in the other direction. An additional circuit is provided between the battery B and the motor M which includes a polarity changing switch b₂ used for fine adjustments and switches 3 and 4. Thus with switches 3 and 4 closed the motor M may be operated either in reverse or forward by manipulating the switch b₂. Suitably coupled to the shaft 7 of the tuning device 8 which is driven by the motor M there are provided a pair of lever devices 5 and 6 representing one station setting and a second pair of lever devices 5', 6' representing a second station setting. The levers 5 and 5' which will be referred to hereinbelow as fixed levers are arranged so as to be adjustable on the shaft 7 in relation to each other and fixed in any desired position by the aid of clamping means such as set screws. The levers 6 and 6' which will be referred to hereinafter as drag levers are freely mounted on shaft 7 and are fitted with pins 9 which cooperate with corresponding slots or grooves formed in the fixed levers 5 and 5' respectively. As shown in Fig. 6 the levers 6, 6' operate normally closed switches 1 and 2 respectively of the switch assembly while the levers 5 and 5' operate normally closed switches 3 and 4. The arrangement is such that the switches 1, 2, 3 and 4 are opened by their respective levers.

The operation of the system is as follows: With the system at rest all four of the contacts 1, 2, 3 and 4 are closed. As previously pointed out coarse adjustment switch a serves to throw the motor into either clockwise or counter-clockwise rotation for coarse adjustment. Switch assembly b is made up of two sections b₁ and b₂, section b₁ is closed when it is desired to operate the motor by the switch a, while section b₂ is open. It should be understood that switches a, b₁ and b₂ are arranged so that when released they assume a central position between their respective contacts, in other words, the switch blades do not contact any of the contacts of the switches. For fine adjustment purposes the switches a and b₁ are released which means that the switches are open and switch b₂ is operated to one or the other of its extreme positions depending upon the direction it is desired to make the correction. The motor energizing circuits may be traced as follows: For coarse adjustment switch b₁ is closed and the motor is energized by battery B for rotation in one direction through a connection from the plus side of the battery B, through lower blade of the switch b₁ now closed, lower blade of switch a it being understood that the

switch is swung down to its lowest position for rotation of the motor in one direction, switch 2, motor M, upper blade of switch a, upper blade of switch b₁, back to the negative side of the battery B. For rotation of the motor in the other direction the switch a is thrown to its uppermost position and the circuit from the battery to the motor is as follows: From the positive end of battery B through lower blade of switch b₁, lower blade of switch a, middle contact of switch a, motor M, switch 1 which is closed, upper contact of switch a, upper blade of switch a, upper blade of switch b₁ back to the negative side of the battery. It is to be understood that when the motor is controlled by means of switch a the switch b₂ is in its released or open position. For fine adjustment purposes the circuit may be traced as follows, it being understood, of course, that the switch b₁ is released which means that the switch is open: For one direction of rotation of the motor the energizing circuit extends from the positive end of the battery B through lower blade and lower contact of switch b₂, switch 3, motor M, middle contact and upper blade of switch b₂ back to the negative side of the battery. For fine adjustment of the motor M in the opposite direction the switch b₂ is thrown to its uppermost position and the energizing circuit is as follows: From the positive side of the battery B through lower blade and middle switch of b₂, motor M, switch 4, upper contact and upper blade of switch b₂, back to the negative side of battery B.

The tie-up between the levers and the switches 1, 2, 3 and 4 is as follows: It is assumed that the element to be adjusted is fixed to the shaft 7 and as previously described levers 5 and 5' are fixed to the shaft 7. The fixed levers have the slots which are engaged by pins 9, 9' of the drag levers 6, 6' it being understood that the drag levers are not fixed to the shaft but may be rotated thereon. The fixed levers 5 and 5' act upon the contacts 3 and 4 while the drag levers 6 and 6' act upon the contacts 1 and 2 as is clearly disclosed in Fig. 6.

In the position shown in Fig. 2 it will be seen that the switch 1 has just been opened by the lever 6 so that the motor comes to rest due to the fact that the motor circuit is broken. Now let us suppose that it is desired to tune the receiver to the station represented by the lever 6'. For this purpose switch b₁ is closed and the coarse adjustment switch a is operated so that the motor will be rotated in a counter-clockwise direction. This starts the shaft 7 rotating counter-clockwise. As the lever 5 passes over the contact 3, the switch 3 will be opened for a short time but this has no action because the switch b₂ is in a released position which means that the battery B is not connected to the motor M through the switch 3. As the shaft 7 continues to rotate counter-clockwise the drag lever 6 is taken up by the fixed lever 5 and rotated with it thus allowing switch 1 to close. However, this is also without effect because the switch a due to the fact that counter-clockwise rotation was desired was swung over to its lowermost position so that switch was not connected to the battery B. As the shaft continues to rotate it carries with it lever 5' which in turn drags along the lever 6'. As the lever 5' passes switch 4 the switch is opened but this is without effect because as previously stated the switch b₂ is in its released position. However, when the lever 6' reaches contact 2 switch 2 is opened, hence the

motor is cut off from the battery B and stops.

If the tuning is not exactly correct, the operator may by operating the switch b₂ correct the tuning position to one side or the other by releasing switches a and b₁ and operating switch b₂ in one direction or the other depending upon the correction desired. The amount of correction available on one side is limited by the contact 3 and on the other side by the contact 4, it being understood that the opening of either of switches 3 or 4 by the lever 5' will stop the motor.

In the positions of levers 5 and 6 shown in Fig. 3 it will be seen that the lever 6 has opened the switch 1 thus stopping the motor and that fine adjustments may be made by operating the switch b₂ after releasing switch b₁. The diagram shown in Fig. 4 illustrates how the lever 5 picks up the drag lever 6, while the diagram in Fig. 5 illustrates all of the four contacts in closed position due to the fact that the levers 5 and 6 are beyond the contact positions.

For application of this arrangement to a greater number of fixed tuning positions, reference may be had to German Patent No. 583,866.

I claim:

1. In a remote control arrangement for radio receiving apparatus and the like, an electric motor for operating the receiver tuning means, a first motor circuit including coarse adjusting means operable to connect the motor to a supply source for rotation thereof, a plurality of operable switches for stopping the rotation of the motor at certain predetermined positions, a plurality of switch operating devices operable with said tuning means and adjustable relative thereto, each of said switch operating devices having coupled thereto through lost motion driving means an auxiliary switch operating device, said auxiliary switch operating devices being disposed relative to said operable switches, a second motor circuit in shunt with said first circuit and including a fine adjustment controller operable to connect the motor to said source for rotation of the motor in either direction and to disconnect the motor from the source to stop the motor, said second motor circuit including limit switch devices for stopping said motor at predetermined limits of operation a small distance from either side of any one of said first named positions, said limit switch devices being disposed for operation by said first named switch operating device.

2. In a remote control arrangement for radio receiving apparatus and the like, an electric motor for operating the receiver tuning means, a supply source for said motor, a first motor circuit including switching means for connecting the motor to the supply source, a plurality of operable switches cooperating with said motor circuit for stopping the rotation of the motor at certain predetermined positions corresponding to the various tuning positions desired, a plurality of switch operating devices operable with said tuning means and adjustable with relation thereto, each of said switch operating devices having coupled thereto through lost motion driving means an auxiliary switch operating device, said auxiliary switch operating devices being disposed so as to operate said operable switches, a second motor circuit including a controller device operable to connect the motor to said source for rotation of the motor in either direction and also to disconnect the motor from the source to stop the motor, limit switch devices in said second motor circuit for stopping said motor at predetermined limits in either direction from any one of said

first named positions, said limit switch devices being disposed for operation by said first named switch operating devices, said limit switch devices being arranged with respect to said plurality of adjustable switch devices so that the motor may be rotated a short distance on either side of the position to which it is adjusted by said first motor circuit.

3. In a remote control arrangement for radio receiving apparatus and the like including a control shaft, a reversible electric motor for operating said shaft and a motor circuit including operable switching means for connecting the motor to a voltage supply source for rotation of the motor in either direction, a pair of normally closed auxiliary switches arranged in said motor circuit so that the motor is energized through one of said auxiliary switches when said operable switching means is operated to rotate the motor in one direction and through the other auxiliary switch when the operable switching means is operated to rotate the motor in the opposite direction, a second motor circuit including operable switching means for connecting the motor to a voltage supply source for rotation of the motor in either direction, a second pair of normally closed auxiliary switches arranged in said second motor circuit so that the motor is energized through one of said second pair of auxiliary switches when the last named operable switching means is operated to rotate the motor in one direction and through the other of said second

pair of auxiliary switches when the last named operable switching means is operated to rotate the motor in the opposite direction, a lever device rotatable with said control shaft and positioned with respect to said second pair of auxiliary switches so that it opens one of said second pair of switches when the shaft is in a predetermined position and the other of said second pair of auxiliary switches when the control shaft is in another predetermined position, and means driven by said lever device through a lost motion means, for opening one of said first pair of auxiliary switches when said control shaft is in any position within a range of positions which includes at least a part of the range bounded by said first two named positions.

4. In an arrangement as described in claim 3, a second lever device rotatable with the control shaft and positioned with respect to the second pair of auxiliary switches so that it opens one of said second pair of switches when the shaft is in a predetermined position and the other of said second pair of switches when the control shaft is in another predetermined position and means driven by said second lever device through a lost motion means, for opening the other one of said first pair of auxiliary switches when said control shaft is in any position within a range of positions which includes at least a part of the range bounded by said last two named positions.

FERDINAND EDUARD LUTZ.
